Application May 17, 1945, Serial No. 594,272

4 Claims. (Cl. 154—42)

1

The present invention relates generally to improvements in the art of producing flat pressure sealed articles in rapid succession, and relates more specifically to an improved system of manufacturing successive bags, pouches or envelopes from a continuous ribbon of sheet stock such as thermoplastic material, paper or the like.

The primary object of my invention is to provide an improved system of rapidly and effectively producing a succession of bags or pouches, with least waste of material and at minimum cost.

Many different types of machines and systems for producing successive bags or pouches from thermoplastic sheet material such as "cellophane" or "Pliofilm," and from paper having local adhesive areas applied thereto, have heretofore been proposed and used commercially with varying degrees of success, but none of this prior equipment has proven entirely satisfactory for various reasons. Most of the prior bag making machines are unable to function so as to produce successive perfect articles at high speed, primarily because the apparatus does not provide for a sufficient period of proper heat and pressure application to the seams or joints which are necessary in the production of the bags or pouches. Others of the previous mechanisms for automatically manufacturing a succession of bags or the like, were relatively complicated and unreliable in operation, and could not be effectively utilized to operate upon different types of stock material. Still others of the prior assemblages for producing such items, could not be readily manipulated and adjusted while in operation so as to insure accurate application of the sealing pressure, and many were not operable at high speed in order to produce the bags at low cost and without excessive attention.

It is therefore a more specific object of the present invention, to provide improved bag making mechanism which obviates all of the above mentioned objectionable features, and which is extremely flexible in its adaptations and reliable in operation.

Another specific object of this invention is to provide an improved bag or pouch fabricating system adapted to convert a rapidly advancing ribbon of various types of stock, into a succession of perfect finished articles, at minimum cost and with least waste of material.

Still another specific object of my invention is to provide an improved bag producing assemblage wherein maximum sealing periods are provided at the seams and joints of the successive bags even when operating at very high speed, and

2

which is capable of being utilized to operate effectively with any sheet stock having pressure sealable local areas or continuous coatings thereon.

These and other specific objects and advantages of the invention will be apparent from the following detailed description.

A clear conception of the several features constituting my improvement, and of the mode of constructing the mechanism and of operating a system embodying the invention, may be had by referring to the drawings accompanying and forming a part of this specification wherein like reference characters designate the same or similar parts in the various views.

15 Fig. 1 is a diagram of a typical bag producing system embodying the invention, depicting diagrammatically the successive steps involved from start to finish;

Fig. 2 is a somewhat diagrammatic considerably enlarged transverse section through the improved pressure and heat applying bar assembly and dwell producing mechanism for sealing the transverse joints of the rapidly advancing stock ribbon;

20 Fig. 3 is a somewhat enlarged end view of the jumping ribbon tensioning or draw roll assemblage utilized in the improved system when operating with non-thermoplastic stock having local thermoplastic or adhesive strips applied transversely to the ribbon;

Fig. 4 is an enlarged fragmentary side elevation of the improved dwell producing mechanism for the sealing bars, showing a fragment of the latter swung into the plane of the view;

25 Fig. 5 is a similarly enlarged end view of the mechanism shown in Fig. 4, illustrating the same in two different positions of adjustment in heavy and light lines respectively; and

Fig. 6 is a somewhat diagrammatic central vertical section through the draw roll and pressure applying mechanism for sealing the transverse joints of the travelling ribbon, the section being taken in the longitudinal plane of advancement of the stock ribbon.

30 While the invention has been shown and described herein as being advantageously applicable to a system for producing successive bags from a continuous ribbon of stock traveling at high speed and adapted to be heat sealed and severed into a succession of bags of any desired definite length, it is not my desire or intent to unnecessarily restrict the scope or to limit the utility by virtue of this specific and typical embodiment.

35 Referring particularly to Fig. 1 of the drawings, the improved bag producing system illus-

trated diagrammatically therein, comprises in general a stock ribbon supply or mill roll 8 consisting of a continuous ribbon 9 of stock; a series of guide rollers 10 coacting with the ribbon 9 to guide and conduct the same past a transverse glue strip applier or cross-paster 11 and a longitudinal adhesive applier or center seam glue wheel 12 in rapid succession; a former disk 13 subsequently cooperable with the ribbon 9 to fold the opposite longitudinal glue coated edge portions thereof inwardly into overlapping coaction with each other, and to direct the folded ribbon horizontally; two laterally spaced pairs 14, 15 of lifting or jumping draw rollers adapted to coact with the horizontal folded stretch of the ribbon 9 after it leaves the former disk 13; a set of upper and lower heat sealers or heated transverse pressure bars 16, 17 cooperable with the local transverse adhesive strips applied to the ribbon 9 by the cross-paster 11, to seal the transverse areas of the folded travelling stock; another set of cooperating draw rollers 18 pressingly coacting with the longitudinal seam and with the transversely heat sealed ribbon 9; a cut-off device 19 for severing the advancing seam sealed ribbon into successive bag lengths; a final set of draw rollers 20 for delivering the severed lengths 21 of the ribbon 9 to a series of revolving speed increasing segment sets 22, 23 cooperating with the severed bag lengths 21 to momentarily augment the speeds thereof and to provide time for finally tucking and gluing the successive bag bottoms; a set of rotating tucking and tuck clamping cylinders 24 coacting with a glue wheel 25 and with a final press roll 26 to tuck and glue the bag bottoms; and a stacking receptacle 27 for the finally completed bags 28.

The cross-paster 11 and seam glue wheel 12 cooperate with transverse glue wheels 29, 30 respectively, in a well known manner to apply transverse and longitudinal strips of adhesive to the stock ribbon 9 at the desired localities when the stock is of a non-thermoplastic type and therefore not adapted to be heat sealed throughout its entire area; but when thermo-plastic stock is used, at least the cross-paster 11 may be omitted. The former disk 13 which is adapted to fold the opposite longitudinal edges of the ribbon 9 inwardly to provide a tubular continuous ribbon of advancing stock, functions automatically as the ribbon 9 is drawn past the revolving disk, and this former as well as the cross-paster 11 and glue wheels 12, 29, 30 are all of well known structure and operation adapted to cooperate with stock ribbons of various widths and lengths, and consisting of diverse materials such as "cellophane," "Pliofilm," a paper, or the like.

The two laterally spaced sets or pair 14, 15 of initial draw rolls, are of special construction as shown more in detail in Figs. 3 and 6, and each pair 14, 15 comprises an upper roll having opposite continuous annular end flanges 31 of slightly greater diameter than the intervening roll, and a lower roll having opposite concentric surfaces 32 of lesser diameter provided with local cam projections 33 adapted to coact with the peripheral cylindrical edges of the corresponding flanges 31 of the adjacent upper roll. These cam projections 33 of the roll set 14 are angularly advanced relative to the corresponding cam projections 33 of the other draw roll set 15, and the rolls of each pair 14, 15 are normally urged toward each other by compression springs 34 thus causing the flanges 31 to normally contact

and roll upon the adjoining surfaces 32 when the projections 33 are inactive as at the right of Fig. 3. However, when the projections 33 of either roll set 14, 15 are active as shown at the left of Fig. 3, the upper roll is momentarily lifted away from the lower roll of the set; but the rolls of only one set 14, 15 are adapted to be thus momentarily separated at a predetermined time thus maintaining at least one pair 14, 15 active as draw rolls at all times. The end bearings for the draw roll sets 14, 15 are mounted in a main frame 35, and the lower draw rolls are adapted to be constantly rotated from a power shaft 36 through a train of gears 37, in the directions indicated; and when the draw roll sets 14, 15 are functioning normally, and in properly timed relation to the speed of travel of the ribbon 9, the rolls of the alternate sets 14, 15 will jump or be automatically separated as each of the successive transverse glue strips applied by the cross-paster 11 passes therebetween, thus preventing the advancing ribbon from sticking to the initial draw rolls while constantly maintaining the draw pull on the ribbon 9.

The complementary set of upper and lower heat sealers or heated transverse pressure bars 16, 17 which is cooperable with the local transverse adhesive strips applied to the ribbon 9 by the cross-paster 11 so as to seal the successive transverse areas of the tubular advancing stock, and the mechanism for moving these bars 16, 17, are also of improved construction and operation and constitute an important feature of my invention. Each of these bars 16, 17 is provided with an electrically heated elongated pressure plate 38 comprising a constantly heated strip of metal having a roughened contact face and being energized in any suitable manner, and each bar 16, 17 is slidably mounted in a cradle 39 and is constantly urged toward the other bar by means of a number of compression springs 40, see Figs. 2 and 6. Each cradle 39 is also provided with four rigid laterally projecting arms 41 each having an anti-friction bearing 42 mounted therein, and these bearings 42 coact with crank pins 43 projecting inwardly from the sides of two pair of intermeshing gears 44, 45 which are journaled for rotation upon the main frame 35 as shown in Figs. 2, 4 and 6. The upper gears 44 are rotatable by the lower gears 45 and the latter are drivingly interconnected by idler gears 46 so that rotation imparted to any one of the gears 44, 45 will obviously be simultaneously transmitted to all of the others and will cause the crank pins 43 to revolve in unison thereby also causing the cradles to revolve in orbits while their bars 16, 17 are always maintained parallel to each other with their pressing faces disposed in horizontal planes at all times, as best shown in the motion diagram of Fig. 2. While the bars 16, 17 are being moved rearwardly out of engagement with each other the springs 40 will push them outwardly in their carrier cradles 39 as far as the stop plates 47 will permit; but as the bars 16, 17 engage the intervening ribbon 9 and are moved forwardly, they recede within their cradles 39 and the heater plates 38 resiliently engage and heat and press the adhesively coated local transverse areas of the ribbon 9 during a dwell period D, see Fig. 2.

As shown in Figs. 4, 5 and 6, the lower gears 45 at the left of the heat sealing assemblage, are adapted to be positively rotated so as to provide maximum dwell periods D, by means of a special motion transmitting mechanism compris-

ing a revolving slide 48 centrally attached to the shaft 49 to which the adjacent gear 48 is also secured, and a crank 50 having a roller 51 mounted upon its revolving crank pin 52 and coaxing with the rectilinear slot 53 of the adjacent slide 48. The shaft 49 is mounted in an anti-friction bearing 54 carried by the main frame 35, while the crank 50 is secured to one end of a counter-shaft 55 which is journalled for rotation in an anti-friction bearing 56 carried by a normally fixed but adjustable bracket 57. A gear 58 is secured to the outer end of the counter-shaft 55 and meshes with a gear 59 carried by the adjacent outer end of a horizontal shaft 60 which is journalled for rotation in the main frame 35; and the bracket 57 is swingably adjustably mounted upon the shaft 60 and is provided with an arcuate adjusting slot 61 with which a clamping cap screw 62 is cooperable in order to lock the bracket 57 in properly adjusted positions. The cap screw 62 penetrates the slot 61 and coacts with a boss 63 rigidly attached to the main frame 35, so that by loosening the screw 62, the bracket 57 may be swung about the shaft 60 as a pivot and the shaft 55 may thus be shifted toward and away from the axis of the shaft 49. The transverse shaft 60 may be driven directly from the power shaft 36 through gearing 64, and is constantly rotat-
ing during normal operation of the machine.

With this assemblage of elements, the heat-
ing and pressure applying bars 16, 17 may be
caused to travel quickly when being carried rear-
wardly and while inactive, and to advance slowly
during the dwell period D and while travelling
forwardly in contact with the ribbon 9. These
rates of rearward travel of the bars 16, 17 and
the duration of the dwell period, may both be
varied by merely adjusting the position of the
bracket 57 and hence the location of the crank
shaft 55 relative to the axis of the shaft 49, with
the aid of the slot 61 and clamping screw 62
coacting therewith, thus permitting the mech-
anism to be adapted for proper cooperation with
bags of various lengths and with ribbons 9 trav-
elling at high speeds. By adjusting the shaft 55
so as to cause its axis to coincide with that of
the shaft 49, the forward and return movements
of the sealing bars 16, 17 will be substantially
equalized; but as these shaft axes are separated
more and more, the return speed of the pressure
bars will increase while the forward speed will
be correspondingly decreased thus also increas-
ing the dwell period D, that is the duration of
the sealing period. While the mechanism for
effecting this adjustment has been shown in sev-
eral positions in Fig. 5, in heavy and light lines
respectively, the bracket 57 would normally be in
approximately the position shown in the heavy
lines and would not ordinarily be swung as far
to the right as actually indicated by the light
line position.

The draw rolls 18 which are disposed forwardly
of the transverse orbitally moving sealing bars
16, 17, may be of a well known type wherein the
lower roll is constantly positively rotated with
the aid of suitable gearing, while the upper roll
is mounted in slidable bearings and is resiliently
urged toward the lower roll by means of adjust-
able compression springs 65, as indicated in Fig.
6. These draw rolls 18 are journalled for rota-
tion in bearing boxes 66 coaxing with the main
frame 35, and the draw rolls 18 besides main-
taining the advancing ribbon 9 in taut condi-
tion, also serve to press the adhesive coated longi-
tudinal seam formed by the opposite overlapped

side portions of the ribbon 9, into sealing con-
dition. The transverse areas which finally con-
stitute the bottom closures of the successive bags
and the longitudinal seams of the bags, are thus
completed in succession while the ribbon 9 is still
in tubular and continuous form, and the draw
rolls 18 thereafter advance the ribbon 9 toward
the cut-off device 19.

The cut-off device 19 may be of any well known
type adapted to shear the ribbon 9 into suc-
cessive equal lengths while advancing at high speed,
and the successive severed lengths 21 of the tu-
bular stock are withdrawn from the zone of cut-
ting by another set of ordinary draw rolls 20 and
are delivered toward the first set of speed ac-
celerating segments 22, see Fig. 1. These speed
increasing segments 22 are also of well known
construction, and after somewhat accelerating
the speed of travel of the severed length 21, the
segments 22 deliver the successive lengths to a
second set of similar accelerating segments 23
which function to still further increase the speed
of advancement of the bag lengths 21 and to
deliver them in succession to the final tucker
25 and bag finishing rolls or cylinders 24. The ac-
celeration of the bag lengths 21 after being
severed from the ribbon 9, is necessary in order
to provide ample time for the cylinders 24 to
finish the bags 28; and the tucking cylinders are
likewise of well known construction and cooper-
ate with the glue wheel 25 and pressing roll 26
to fold or tuck the previously sealed ends of the
successive lengths 21, to apply adhesives to the
tucks, and to press the tucks to the adjacent bag
walls, thereby finishing the bags 28 and deliver-
ing the completed articles in rapid succession to
the stacking receptacle 27.

While the normal operation or successive steps
of my improved bag making system should be
quite apparent from the foregoing detailed de-
scription, a short résumé thereof will be given.
During such normal operation, the draw rolls 14,
15, 18, 20 and the segments 22, 23 will be rotating
to withdraw the stock ribbon 9 from the mill roll
8, and to advance the same past the cross-paster
11, longitudinal seam glue wheel 12, and the
former disk 13 in succession. The speed of travel
of the ribbon 9 as determined by the speed of ro-
tation of the draw rolls, will definitely establish
the final length of the successive bags 28, and this
speed may be as high as two hundred and
fifty feet per minute in actual practice. As the
ribbon 9 proceeds past the cross-paster 11, trans-
verse strips of adhesive are applied at equally
spaced intervals, and in passing the seam glue
wheel 12, a longitudinal glue strip is likewise ap-
plied to one edge of the ribbon. When advancing
past the former disk 13, the opposite longitudinal
edge portions of the continuous ribbon 9 are
folded inwardly and overlapped with the longi-
tudinal glue strip between the superimposed
folds, and the tubular ribbon thus produced is
subsequently drawn past the initial draw roll
sets 14, 15.

While advancing past these roll sets 14, 15 it
is desirable to avoid contact between the rolls
and the externally exposed transverse strips of
adhesive which have been applied to the ribbon 9
by the cross-paster 11, and the cam projections
33 associated with the lower rolls 14, 15 and co-
acting with the flanges 31 of the upper comple-
mentary draw rolls, positively prevent such un-
desirable contact between the draw rolls and
the glue coated areas. However, by virtue of the
relative positions of the projections 33 on the

several roll sets 14, 15, only the rolls of one of these sets will be separated at a given instant, and the rolls of one set 14, 15 will therefore be effective at all times, thus insuring constant draft tension on the ribbon 9. After passing the initial draw roll sets 14, 15, the tubular ribbon 9 is delivered to the transverse sealing zone between the heated pressure bars 16, 17 and the heating and pressing plates 38 of these bars clamp the successive adhesive cross-strips therebetween, and firmly seal the tubular ribbon at these strips. By properly adjusting the bracket 57 and hence the position of the crank shaft 58 relative to the axis of the shaft 49, the plates 38 may be caused to accurately cooperate with the successive transverse glue strips of the ribbon 9; and the dwell period D which is produced by the orbital travel of the bars 16, 17 insures most effective sealing of the successive cross-seams even when the ribbon 9 is travelling at high velocity.

As the cross-seamed ribbon 9 proceeds beyond the heat sealing zone, the draw rolls 18 become effective to press the longitudinal seam of the constantly advancing tubular ribbon, whereupon the ribbon is delivered to the cut-off device 19 and is severed into successive equal bag lengths 21 each having one end closed by a transverse sealed strip area. The successive severed lengths 21 are thereafter delivered by the final draw rolls 20 to the accelerating segments 22, 23 which rapidly remove the lengths 21 from the zone of cutting and deliver them in succession to the final tucking and gluing cylinders 24. The finished bags 28 are delivered in rapid succession by the cylinders 24 past the press roll 26 to the stacking receptacle 27, thus providing a system for automatically and effectively converting the constantly and rapidly advancing stock ribbon 9 into completed bags 28 of uniform length and of durable construction.

From the foregoing detailed description of the specific construction and operation of the improved bag making apparatus, it should be apparent that my present invention provides an improved system of fabricating successive bags 28 of any desired length in rapid succession and without waste of material. The improved mechanism for heating and pressing the successive cross-seams, provides for most effective and accurate clamping and pressing of the transverse adhesively coated areas, regardless of the speed of operation or of the bag lengths; and the pressure applied during each prolonged dwell period D is substantially uniform at all times. The distance travelled by each cross-seam during the dwell and sealing period D is always equal, but, the time involved in each dwell varies slightly in accordance with the speed of operation of the mechanism, and may be prolonged by merely adjusting the bracket 57 with the aid of the clamping screw 62 coacting with the slot 61. The parallel disposition and orbital movement of the bars 16, 17 combined with the slow forward and quick return motion thereof, result in most effective sealing pressure application at all times, and may be utilized to commercially seal seams while the ribbon 9 is travelling approximately fifteen thousand feet per hour, and such speeds have heretofore been impracticable with revolving and reciprocating sealers.

The jumping draw roll sets 14, 15 may also be utilized to good advantage when operating upon non-thermoplastic stock to which local adhesive cross strips are applied in spaced succession, but it is to be noted that the use of the improved

heat sealing bars 16, 17 is not limited to operation on such stock, and these bars 16, 17 and the mechanisms for actuating the same may be just as advantageously employed when operating with thermoplastic ribbon stock such as "cellophane," "Pliofilm," or the like. The fact that the heat sealing is accomplished before the ribbon 9 is severed into sections or lengths 21, eliminates waste of material due to sticking of the severed length to the heat sealing bars, and the draw rolls 16, 17 on opposite sides of the sealing zone positively prevent the ribbon stock from clinging to the pressure bars 16, 17 since they maintain the intervening portion of the ribbon 9 in stretched and taut condition. The improved mechanism also obviates all back lash or whip in the ribbon stock, at all times, even when operating at high speed and with delicate material; and while the improved system may utilize final tucking and gluing of the bag bottoms, as shown, it is just as applicable to the manufacture of bags or pouches wherein such tucking is omitted.

The present improvement has proven highly successful and satisfactory in actual commercial use, and is exceedingly flexible in its adaptations; and the improved mechanism after having been properly adjusted requires no great attention and functions automatically. The assemblage is obviously simple, compact, and durable in construction, besides being highly efficient in operation especially when operating at high speed, and very little waste of material occurs after proper initial adjustments have been made. Such adjustments may also be readily effected while the machine is in operation, and change-over from bags 28 of one length to shorter or longer bags may also be quickly and conveniently accomplished.

It should be understood that it is not desired to limit this invention to the exact steps of the system or to the precise details of construction and operation, herein shown and described, for various modifications within the scope of the appended claims may occur to persons skilled in the art.

I claim:

1. In a bag making system, means for advancing a flattened tubular ribbon of material longitudinally along a rectilinear path, a pair of elongated parallel carrier cradles simultaneously revolvable at like speeds but in opposite directions entirely on opposite sides of said path, a sealing bar carried by an intermediate portion of each of said cradles and revolvable therewith on the same side of said path as its respective cradle, said bars having flat faces spanning and engageable with the opposite sides of successive transverse areas of the advancing ribbon and being suspended from their carrier cradles so as to constantly maintain said faces parallel to said path, two sets of oppositely rotatable gears disposed on opposite sides of said path, each gear of each set having a crank coacting with an end of the cradle disposed on the corresponding side of said path for revolving said cradles, and means for driving said gears to cause said bars to advance with a slow forward motion while said faces engage the ribbon and with a more rapid return motion while out of contact with the ribbon.

2. In a bag making system, means for advancing a flattened tubular ribbon of material longitudinally along a rectilinear path, a pair of elongated parallel horizontally disposed cradles simultaneously revolvable at like speeds but in opposite

directions entirely on opposite sides of said path, a sealing bar carried and revolvable by the mid-portion of each of said cradles on the same side of said path as its respective cradle, said bars having flat faces spanning and engageable with the opposite sides of successive transverse areas of the advancing ribbon and being resiliently retractable relative to their carrier cradles while contacting the ribbon and with said faces constantly maintained parallel to said path, two sets of oppositely rotatable intermeshing gears disposed on opposite sides of said path, each gear of each set having a crank pin coacting with an end of the cradle disposed on the corresponding side of said path for revolving said cradles, driving means coacting with said gears to cause said bars to advance with a slow forward and a quicker return motion, and means cooperating with said driving means to vary the speed of movement of said cradles and the distance between successive ribbon contact areas.

3. In a bag making system, means for advancing a flattened tubular ribbon of material longitudinally along a rectilinear path, a pair of elongated parallel carrier cradles simultaneously revolvable at like speeds but in opposite directions entirely on opposite sides of said path, a sealing bar carried by an intermediate portion of each of said cradles and revolvable therewith on the same side of said path as its respective cradle, said bars having flat faces spanning and engageable with the opposite sides of successive transverse areas of the advancing ribbon and being suspended from their carrier cradles so as to constantly maintain said faces parallel to said path, two sets of oppositely rotatable intermeshing gears disposed on opposite sides of said path, each gear of each set having a crank pin coacting with an end of the cradle disposed on the corresponding side of said path for revolving said cradles, a revolving slide for driving said gears, a driving crank having a revolving pin coacting with said slide, an adjustable bracket rotatably supporting said driving crank, and gearing for rotating said driving crank, said bracket being adjustable to vary the distance between the axes of revolution of said slide and pin and to thereby vary the contact periods of said bars with the ribbon.

4. In a bag making system, means for advancing a flattened tubular ribbon of material longitudinally along a rectilinear path, a pair of elongated parallel cradles simultaneously revolvable at like speeds but in opposite directions entirely on opposite sides of said path, a sealing bar carried by an intermediate portion of each of said cradles and revolvable therewith on the same side of said path as its respective cradle, said bars having flat faces spanning and engageable with the opposite sides of successive transverse areas of the advancing ribbon and being suspended from their carrier cradles so as to constantly maintain said faces parallel to said path, oppositely rotatable intermeshing gears disposed on opposite sides of said path, each gear having a crank pin coacting with an end of the cradle disposed on the corresponding side of said path for revolving said cradle, a revolving slotted slide for driving said gears, a driving crank having a revolving roller coacting with the slide slot, a bracket swingably adjustable about an axis and rotatable supporting said driving crank, and a gear journaled in said bracket for rotating said driving crank, said bracket being adjustable about said axis to vary the distance between the axes of revolution of said slide and roller and to thereby vary the contact period of said bars with the advancing ribbon.
